UNITED STATES PATENT OFFICE.

JOSEPH KENNEDY, OF RICHMOND HILL, NEW YORK, ASSIGNOR, BY MESNE ASSIGNMENTS, TO THE ORSSEE CO., INC., OF NEW YORK, N. Y., A CORPORATION OF NEW YORK.

BOLT-ANCHOR.

1,352,200.

Specification of Letters Patent. Patented Sept. 7, 1920.

Application filed August 20, 1917. Serial No. 187,065.

To all whom it may concern:

Be it known that I, JOSEPH KENNEDY, a citizen of the United States of America, and a resident of Richmond Hill, county of 5 Queens, and State of New York, have invented certain new and useful Improvements in Bolt-Anchors, of which the following is a specification, reference being had to the accompanying drawings, forming a part thereof.

10 This invention relates to an improved bolt anchor for securing a threaded element as a bolt or other fastening device in an aperture in a wall or other building construction 15 of brick, stone, cementitious material and the like.

My improved anchor in its broadest aspects is designed to utilize the combined advantages and beneficial effects of one or 20 more plugs or socket members of relatively hard or resistant material, at least one of which is adapted to receive and hold a bolt or other fastening device; and one or more deformable sleeves of relatively soft material swaged or crowded into the space between the plug or plugs and the walls of 25 the anchorage aperture, whereby the plug or plugs are gripped and firmly held in the wall or building construction.

30 A great advantage of a sleeve or sleeves of soft metal, lies in the fact of the tenacious hold of the metal upon the roughened surface of the wall and upon the exterior of the wall plug, and also in the fact that the soft metal readily accommodates itself to all the 35 irregularities of shape.

In my device, those plugs of relatively hard or resistant material which do not actually receive and hold the bolt, act to 40 form guides or centering devices for the bolt, and the deformable sleeve or sleeves of relatively soft material are preferably separate and independent from the plugs and are swaged or crowded into contact with 45 each other and displaced laterally, in the space between the plug or plugs and the walls of the anchorage aperture by endwise pressure between the plugs. The swaging and crowding of the soft metal may be aided 50 with a suitable tool, if desired, although in the present form of the invention, this would not be necessary.

My device is extremely practical and cheap to manufacture.

In order that my invention may be thoroughly understood I will now proceed to describe the same in the following specification, and then point out the novel features thereof in appended claims.

Referring to the drawings:

Figure 1 is a longitudinal sectional elevation of a device embodying my invention with the parts thereof shown in place within an aperture in a wall and shown in the relative positions and in the condition before expansion.

Fig. 2 is a similar view of the same parts after expansion.

Fig. 3 is a longitudinal sectional elevation of a slightly modified form of construction with the parts shown in the positions and condition they assume after expansion with a bolt in place holding an object against the wall.

Like characters of reference designate 75 corresponding parts in all the figures.

A designates a portion of a wall or other building construction, of brick, for instance, and B the hole for the anchor. t is an interiorly threaded plug of hard metal provided with a base flange u against which is seated a deformable sleeve v of relatively soft metal, such, for example, as lead or an alloy of lead. Another deformable sleeve w bears against the sleeve v and the meeting 85 edges x of these sleeves are preferably beveled. Another guiding and centering plug y is inserted in the outer end of the sleeve w. This has an enlarged portion adapted to fit the hole B and forming a shoulder z which 90 abuts against the end of the sleeve w. The sleeves v and w are swaged and crowded into the anchorage aperture by driving in the outer plug y or by drawing the plugs t and y toward each other by the insertion of a 95 bolt.

The construction shown in Fig. 2 is substantially like that shown in Fig. 1 except that a single deformable sleeve C is shown instead of a plurality of sleeves as indicated 100 in Fig. 1. In Fig. 2 the sleeve C is shown swaged and crowded into the anchorage aperture and filling the irregularities of the walls of the aperture.

Fig. 3 shows a construction similar to 105 that shown in Fig. 2 but the parts of the plug t' and y' which fit within the sleeve C are longer than those of the former case so

that they nearly or quite meet after expansion. This figure also shows a bolt O in place holding an object P against the wall.

This application is a continuation in part 5 of application for a patent filed by me on the 13th of August, 1914, and given Serial No. 856,612.

What I claim is:

1. Means for anchoring a bolt or other 10 fastening device in an aperture in a wall or other building construction, comprising a plug of hard metal having a flange and a smaller non-tapering portion, said flange forming an outwardly facing shoulder, a 15 similar plug having a flange and a smaller non-tapering portion, said flange forming an inwardly facing shoulder, and a separate independent deformable hollow sleeve of relatively soft material arranged between 20 said shoulders and fitting over the smaller non-tapering portions of the plugs, and means for moving said plugs toward each other to thereby cause outward expansion of the sleeve by longitudinal pressure of said 25 shoulders thereon.

2. Means for anchoring a bolt or other fastening device in an aperture in a wall or other building construction, comprising an internally threaded plug of hard metal having a flange and a smaller non-tapering portion, said flange forming an outwardly facing shoulder, a similar plug provided with a central clearance hole having a flange and a smaller non-tapering portion, said flange 30 forming an inwardly facing shoulder, and a separate independent deformable hollow sleeve of relatively soft material arranged 35

between said shoulders and fitting over the smaller non-tapering portions of the plugs, and a bolt adapted to pass through the clearance hole in one of said plugs and to engage the threads of the other plug arranged to move said plugs toward each other to thereby cause outward expansion of the sleeve by longitudinal pressure of said shoulders 45 thereon.

3. Means for anchoring a bolt or other fastening device in an aperture in a wall or other building construction, comprising an internally threaded plug of hard metal 50 having a flange and a smaller portion, said flange forming an outwardly facing shoulder, a similar plug provided with a central clearance hole having a flange and a smaller portion, said flange forming an 55 inwardly facing shoulder, and a pair of independent deformable hollow sleeves of relatively soft material arranged between said shoulders and fitting over the smaller 60 portions of the plugs, the outer ends of said sleeves fitting against said shoulders and with their inner ends projecting beyond the smaller portions of the plugs, beveled inwardly and abutting against each other, and a bolt adapted to pass through the clearance hole in one of said plugs and to engage the threads of the other plug. 65

In witness whereof, I have hereunto set my hand this 14th day of August, 1917.

JOSEPH KENNEDY.
